ABSTRACT: An orthopaedic shoe has a retaining strap. When the shoe is fitted to the foot the strap is secured to the inner edge of the sole directly below the ankle joint and extends outside the upper diagonally over the top of the forefoot, and is secured at the other end to the outer edge of the sole adjacent to the joint of the fifth toe, thus providing a brake against the downward thrust of the soleus at the upper end of the longitudinal arch.

ORTHOPAEDIC SHOES

It is common to find footwear with crossed or uncrossed retaining straps, the objective of which is the securing of the footwear on the foot and preventing the foot from sliding on the sole of the footwear.

The oldest model dates back to antiquity and some variation or other of it is still the most common footwear in the world today. It is essentially a sandal in which the upper ends of the longitudinal straps are attached upon the outer edges of the upper part of the sole on either side at varying distances from the toe of the sandal. These straps cross over the top of the forefoot to the opposite side to fasten by their lower ends to the sole near to or upon the heel section of the sole of the sandal. A further strap may or may not be present which connects the longitudinal straps by a strap which curves behind the heel. The object of the heel strap is to further secure the heel section of the sole of the sandal to the foot.

It is also common to find shoes with uppers in which the retaining strap(s) are attached at varying points along the inner sole or more commonly as extension straps of the inner wall of the upper which cross over the top of the forefoot to fasten by some device to a counter strap from the outer sole or as an extension of the outer wall of the upper. Or the strap may be extensible which obviates the necessity of a fastening device.

My invention is an improved retaining strap which supplements the inherent tensile braking tendons of the foot itself.

Be it said that all retaining straps and uppers of shoes have functioned to a degree as supplementary brakes without being designed to serve that function. This effect is incidental or accidental. There has been no assured consistency nor adequacy of this function by any footwear. The essence of my invention is the specific construction and arrangement of a retaining strap which provides tensile braking action of assured degree and quality. The action and effects of a strap attached according to my specification can only be appreciated by understanding the dynamics of the foot and the action of its inherent tensile braking tendons.

The optimal, i.e. the most nearly physiological, course of the foot in walking has been established. It does not proceed on a straight forward horizontal plane from heel to toe, rather it follows a double zigzag forward torquing course, beginning at the back of the heel, outward and downward along the outer plantar surface of the heel followed by a reversing torque through the ankle and tarsals to the inner longitudinal arch at the upper end of which it is again given a reverse torque outward to continue through the long axis of the first toe and fanning minimally through the lateral four toes.

Achievement of this optimal course is dependent upon the adequately phased correction of the momentum and direction set into motion by gravity and the power of the prime propulsion muscle of the calf — the soleus — through feedback from pressure, tension and stretch sensors in muscles and tendons to the inherent tensile braking tendons of the foot.

The overall momentum and direction of this course is determined by relationship between the direction of the gravitational fall of the superimposed body weight and the power and action of the main propulsion muscle (soleus). The anatomic arrangement of this muscle is such that it elevates the outer half of the heel producing an inward and downward torque in the direction in which the weight load is transmitted through the ankle and tarsals and through them to the outer side of the heel of the opposite foot.

For the sake of description of the inherent braking tendons the above outlined optimal course will be considered as consisting of three distinctly separate phases whereas in reality they flow one into the other, beginning at the heel.

The first phase consists of the outward and downward torquing motion from the back of the heel along its outer plantar surface. The momentum of this phase is derived from the shift of the body weight towards the outside of one foot and from the active thrust of the soleus of the opposite foot. The main tendons which brake this motion are three in number, one of which is suspensory cable circling under the under sur-

face of the outer ankle bones, the others are tensile but not suspensory tendons.

The second phase consists of the reversing torque through the ankle and tarsals to the longitudinal arch. The momentum of this phase is derived from the gravitational shift of the weight to fall on the back of the heel of the opposite foot and from the onset of the contraction of the soleus of the foot in question. The main tendons which brake this motion are also three in number, all of which are suspensory cables which circle under the undersurface of the inner ankle bone and under the undersurface of the lower arch and toe bones. By the end of this second phase most of the weight has been transferred to the opposite foot.

The third phase consists of the outward torquing which begins at the upper end of the longitudinal arch and then continues along the length of the metatarsal to the first toe and through its long axis to the pad at its tip and through the lateral metatarsal heads to the pads on the tips of the lateral four toes. The momentum at this phase is chiefly derived from muscle power and not from gravity. The power thrust is generated by the continuing contraction of the soleus to which is added the thrusting power of the muscles involved in pressing the pads of the toes to the ground. To obtain the maximal pushoff through the pads of the toes the correct alignment of the upper part of the longitudinal arch is essential. In detail the critical area consists of the joint area between the upper end of the central bone of the longitudinal arch (the medial cuneiform) and the lower end of the first metatarsal — the metatarso-cuneiform joint. This critical area is not provided with a suspensory brake of the nature of those in the lower part of the foot as the weight-sustaining factor is scarcely required, the weight having been largely transferred to the opposite foot. It is, however, provided with a relatively small tensile torquing muscle — the tibialis anticus. The tendons of this muscle are thin and so attached that they can sustain but a minimum of stretch, only sufficient to trigger the feedback to initiate the alining countertorque but not sufficient to adequately sustain the inward and downward torque of the soleus thrust.

My invention is primarily concerned with supplying this critical, inherently weak area with a synthetic tensile brake against the power thrust of the soleus to support the tibialis anticus in its alining function.

While the strap is designed to exert the maximal effect at the metatarso-cuneiform joint its braking action begins farther back at the ankle thus it acts as a supplementary brake to the suspensory tendons of the ankle as well.

To ensure that the strap exerts the optimal braking effect at the metatarso-cuneiform joint correct obliquity of its course must be adhered to. The correct obliquity is obtained by its attachment to the sole according to my invention.

In a shoe with an enclosed upper the usual reinforcements of the outer and inner walls of the heel section of the upper are usually sufficient to supplement the tensile braking action of the ankle cradling tendons of phases one and two. In transition to and during the third phase the usual inner wall of the upper does not supply the required, i.e. the correct, tensile brake for the above-described weak area. My invention is designed to perform this function in a shoe with an enclosed upper.

It consists of a shoe having a strap which is so attached as to phase in a braking action against the inward and downward thrust of the soleus sufficient to prevent over stretching the tibialis anticus, permitting feedback from pressure tension and stretch sensors to stimulate the necessary muscle contraction which alines the joint in preparation for the recruitment of the thrust muscles of the toes.

The invention is hereinafter more particular described and is illustrated in the annexed drawings in which:

FIG. 1 is a view of the inner side of a shoe made in accordance with this invention showing the bones of the foot in fine lines;

FIG. 2 is a view of the other side of the shoe shown in FIG. 1; and

FIG. 3 is a plan view of the shoe shown in FIG. 1.

In the drawings corresponding numerals refer to corresponding parts in the various views.

The shoe comprises a sole 1 and an upper 2. The sole 1 has a raised heel portion 3. The upper comprises a toe portion and a heel portion and encompasses the foot below the ankle. The sole, heel and upper may be made of leather or other suitable material.

A strap 4 embraces the foot of the wearer. The strap may be formed of leather, plastic, canvas, or other pliant but substantially nonexpansive material. As shown in FIG. 1, the strap is secured at one end at the outer edge of the sole immediately in front of a line A perpendicular to the lower (posterior) margin of the ankle joint 5 when the shoe is fitted on the foot. As shown in FIG. 3, the strap extends outside the upper, diagonally over the top of the forefoot above the metacarpocuneiform joint 6, and is secured to the inner edge of the sole of the shoe opposite the metatarso-phalangeal joint 7 of the fifth or little toe, as shown in FIG. 2. This is the joint where the little toe attaches to the forefoot. The strap is of such strength, width, and length that it firmly engages the foot over a substantial area and provides a braking action against the inward and downward thrust of the soleus at the medial metatarso-cuneiform joint sufficient to enable the tibialis anticus to come into play to align the joint in preparation for the recruitment of the thrust muscles of the toes.

Preferably the strap 4 is formed in two parts connected by a lacing or buckle 8, or other securing means, which is adjustable whereby the tension of the strap can be varied.

The width of the strap must be such that it will firmly embrace the foot without cutting into the flesh. In practice the width of the strap should be not less than one-quarter of an inch. The strap may be uniform in width, but preferably on the inner side of the shoe it is flared as shown in the drawings and secured to the sole along a line from the point of heel attachment to a point about one-half of an inch heelward from the first metatarso-phalangeal joint 9 (the joint where the big toe attaches to the forefoot).

The strap is separate from the upper although it may be attached to it. The strap is secured to the sole by a line of stitching 10 on the inside of the shoe and 11 on the outside of the shoe. The length and proportions of the strap must be such as to give the desired support to the foot of the wearer and in many cases the shoe and strap must be specially fitted or made to order for the wearer. However, standard sizes may be produced and used by persons whose feet are of standard size and configuration, particularly when the strap is provided with

an adjustable fastener, whereby the length of the strap may be adjusted so as to engage the foot with the required supporting action.

No details of the construction of the shoe or of the method

5 of securing the strap to the shoe are shown since these are ordinary shoemaking practices. Instead of having the strap sewn directly to the sole, it may be secured to the sole through the intermediary of the upper. Likewise, the strap and the upper may be secured or sewn together at any point where the strap 10 overlaps the upper.

I claim:

1. A shoe having a sole, an upper, and a pliant but substantially nonexpansive strap secured at one end on the inner edge of the sole immediately in front of a line perpendicular to 15 the lower (posterior) margin of the ankle joint when the shoe is fitted on the foot, and extending separate from and outside the upper diagonally over the top of the forefoot above the metacarpocuneiform joint and secured at the other end to the outer edge of the sole opposite the metatarso-phalangeal joint 20 of the fifth toe (the joint where the little toe attaches to the forefoot), said strap being of such strength, width, and length that it firmly engages the foot over a substantial area and provides a braking action against the inward and downward thrust of the soleus sufficient to enable the tibialis anticus to come 25 into play to align the joint in preparation for the recruitment of the thrust muscles of the toes.

2. A shoe constructed as claimed in claim 1 in which the strap on the inner side of the shoe is flared and secured to the sole along a line from the point of the heel attachment to a 30 point about one-half inch heelward from the first metatarso-phalangeal joint (the joint where the big toe attaches to the forefoot).

3. A shoe constructed as claimed in claim 1, in which the strap is formed of two parts provided with means for securing 35 the parts together, which securing means are adjustable whereby the tension of the strap may be varied.

4. A shoe constructed as claimed in claim 2, in which the strap is formed of two parts provided with means for securing the parts together, which securing means are adjustable 40 whereby the tension of the strap may be varied.

5. A shoe constructed as claimed in claim 1 in which the strap is formed partially of the upper.

6. A shoe constructed as claimed in claim 1 in which the strap is secured to the sole through the intermediary of the 45 upper.

UNITED STATES PATENT OFFICE
CERTIFICATE OF CORRECTION

Patent No. 3,543,764 Dated December 1, 1970

Inventor(s) Hilkka O. Hormavirta

It is certified that error appears in the above-identified patent and that said Letters Patent are hereby corrected as shown below:

Column 4, line 12, "plaint" should read -- pliant --.
